COMBINED LITTER CONTAINER AND ADVERTISING DISPLAY DEVICE

Walter Kay, 815 S. 18th St., Arlington, Va., and Raymond M. Poelvoorde, Birmingham, Mich.; said Poelvoorde assignor to said Kay

Filed Feb. 14, 1972, Ser. No. 226,383

Term of patent 14 years

Int. Cl. D20—99

U.S. Cl. D7—191

FIG. 1

FIG. 2

FIG. 4

FIG. 1 is a perspective view of a combined litter container and advertising display device showing my new design.

FIG. 2 is a perspective view of the container in open position with the side wall construction partially broken away for illustrative purposes only.

FIG. 3 is a side elevational view of the closed container; and

FIG. 4 is a bottom plan view.

We claim:

The ornamental design for a combined litter container and advertising display device, substantially as shown and described.
